ATTORNEYS

UNITED STATES PATENT OFFICE

BEN J. HERGET, OF ST. LOUIS, MISSOURI

TOOTHBRUSH

Application filed September 1, 1928. Serial No. 303,403.

This invention relates to tooth brushes of the type in which a permanent clamping handle is employed with an adjustable and removable brush head.

5 An object of this invention is to provide an improved tooth brush structure, and particularly an improved handle for use with a brush of the type mentioned; and to provide such a handle with clamping means consisting of relatively few component parts, of inexpensive construction and arranged for ease of manipulation; the clamping means being arranged for retaining, in adjustable and detachable engagement, a brush head 10 having a projecting element for effecting an operative union with the handle.

A further object is to provide a tooth brush assembly, including a frictional clamping mechanism, with improved means for substantially enclosing such mechanism for sanitary reasons, and to avoid any possibility of abrasion of the oral membranes by exposed clamping elements.

15 A still further object is to construct a tooth brush assembly of the recited type, in such a manner that the parts may be inexpensively formed from standard tubular stock, for example, metal or bakelite tubing of standard diameters, and wire or other round stock of 20 standard gauge.

Further objects and advantages of the invention will appear from the following illustrative description of parts and the accompanying drawing, in which:

25 Fig. 1 is a side elevation of a preferred embodiment of my invention; Fig. 2 is an enlarged fragmentary sectional elevation, clearly illustrating the construction of the brush holding elements.

30 Referring by numerals to the drawing, the handle 5 may be of tubular construction, as shown, is preferably of uniform section, and may be provided with a closure member 6, to which, if preferred, may be joined a ring, hook or the like by which the brush may be suspended when not in use. The handle may, if desired, be curved and flattened to conform to the hand of the user, and may be formed of any desired material. Preferably permanently secured to, and forming an integral

part of the opposite end of the handle 5, is an extension or nut 7, provided with a threaded internal axial bore 8, and provided exteriorly with a circumferential bearing surface 9. The bearing surface is, by preference, of slightly reduced diameter forming a shoulder 10, in such a manner that the diameter of the threaded extension 7 adjacent the handle, is substantially equal to that of the handle. 35 Rotatably disposed on the bearing surface 9, is a sleeve or shroud 11, one end of which abuts shoulder 10. The sleeve 11 is formed with oppositely tapered portions on each side of a relatively restricted portion, and its end, opposite the handle, is slightly flattened to form a fan-tail portion 12, for the purpose of receiving and maintaining in parallel aligned relation, a pair of arms 13 and 14 of a clamping element. These arms are joined to form a loop 15, having a diameter normally slightly in excess of the diameter of a stud 16 on the brush head, which the loop is adapted to engage. The clamping element is by preference formed of a suitable metal wire stock, having a certain inherent resilience, so that when the loop 15 is released from the brush stud 16, the brush is readily removable from, and angularly adjustable in, the loop. From the construction described, it will be seen that the sleeve 11 is maintained in operative position on the brush handle by means of engagement between a threaded portion 17, on the clamping element, with the internally threaded bore 8 in the extension nut associated with the handle.

40 By rotating the handle in the proper direction relative to the brush head and sleeve, the clamping member will be drawn inwardly, or toward the handle, the effect of the portion 12 of the sleeve on the arms 13 and 14, being to constrict or tighten the loop portion 15 about the upstanding stud 16 on the brush head, thus holding the brush in frictional clamping engagement, and in any desired angular relation with respect to the handle. Obviously, relative motion between the sleeve 11 and the clamping element is prevented by the manner of engagement of the fan-tail portion of the sleeve with the arms 13 and 14, so that these parts rotate to 45 50 55 60 65 70 75 80 85 90 95 100

gether in effecting adjustment between the brush head and the handle.

Upon a relatively slight rotative movement of the handle with respect to the sleeve and clamping member, the brush head and clamping member will be extended sufficiently from the sleeve, for the loop 15 and arms 13 and 14 to release the brush head for free adjustable movement thereof, to any desired angular setting. A slight tightening rotation of the handle again serves to maintain the adjusted angular setting of the brush head and handle. A slightly greater releasing rotation of the handle or sleeve, serves to free the brush head and stud entirely from the loop 15, to permit the removal of a worn brush element and the ready insertion of a replacement brush head.

An objection to prevailing brush clamping means for purposes analogous to that of the present construction, is the fact that such clamps are often exposed, with the result that surface irregularities of the clamping mechanism are apt to injure the delicate membranes of the mouth and gums. The present construction affords a smooth, gradually tapering, exterior surface so as positively to avoid any chance of injury from projecting metal parts. The present construction is conducive to ease of cleansing the brush assembly, since the entire mechanism may be disassembled by relatively rotating the handle and sleeve; and the tubular construction of the sleeve, with its related parts, greatly facilitates cleaning. The described assembly provides a brush handle which is easily cleaned, attractive in appearance and of inexpensive construction, in fulfillment of the objects set forth above.

I claim as my invention:

1. In a tooth brush structure, a handle, a brush holding element carried thereby, and having an open, partly circular loop adapted to receive a brush element in relatively rotatable relation, and having an elongate threaded leg extended toward the handle, a tubular spacing member mounted for rotation relative to the handle and disposed between the loop portion of said holding element, and said handle, coacting portions including a free, resilient leg adjacent the loop on said holding element, a flared end portion on the spacer member and an internally threaded portion on the handle, said portions adapted, upon relative rotation of the spacing member and handle, to permit an adjustable detachable engagement of a brush, by said holding element.

2. In a tooth brush structure, a handle, a holding element carried thereby, and including an open loop adapted rotatably to receive a brush, one free end of the loop being extended toward the handle into threaded engagement therewith, and a combined cover for said holding element and spacer between

portions of said handle and holding element, adapted for rotation relative to the handle, and coacting means constituted by the handle, another free end of said loop, and the spacer adapted upon said rotational movement, to vary the pressure of said spacer upon the loop portion of the holding element, whereby to permit an adjustable and detachable engagement of a brush by said holding element.

3. A tooth brush structure including a brush portion, a handle, a holding element threadedly engaging the handle, and including an open loop pivotally associated with the brush portion, a sleeve engaging said handle and substantially enclosing the holding element, and adapted to be axially rotated with said holding element and relatively with respect to said handle, the sleeve having a portion bearing laterally against said loop and adapted, upon such rotation, selectively to tension the holding element, whereby to permit of angular adjustment of the brush portion with respect to the handle.

4. A tooth brush structure including an adjustable brush head and a handle therefor, a connecting element engaging the brush and handle, formed of a length of material of substantially uniform section, the brush-engaging end being bent upon itself to form an open loop with paired tapered legs extending therefrom toward the handle, a member substantially enclosing the connecting element and arranged for axial rotation, relative to the handle, said member having a tapered open end portion adapted, upon such rotation, to bear, in actuating relation, upon one of the legs of the connecting element, to permit selective tension engagement between the brush head and handle and to permit removal and replacement of the brush head.

5. A tooth brush structure including a handle, a variable tension clamp for detachably securing a brush head in adjustable relation to the handle, a tubular member substantially enclosing said clamp, said member being rotatable relative to the handle, and endwise displaceable relative to the clamp, said member having an end portion adapted selectively to actuate the clamp upon movement relative thereto, and coacting means carried by the clamp and handle, adapted to effect a selective tension adjustment of said clamping element, upon axial rotation of said member relative to the handle.

6. In a tooth brush structure including an angularly adjustable brush head, a handle, a member associated with the handle forming a threaded longitudinal bore, a combined clamping and securing member for said brush head, formed of a rod material of substantially uniform section, one end portion of which is bent upon itself to form an open loop, with a pair of leg portions extending from one side of the loop in rela-

tively tapered relation, one of the leg portions terminating adjacent the loop, and the other leg having a threaded portion adapted to engage said threaded bore, and an enclosing sleeve for the leg portions of the clamping member, axially rotatable with respect to the handle, the end portion of said sleeve engaging the leg portions of said clamping member near said loop, and adapted to constrict the loop with respect to said brush head.

7. In a tooth brush structure, a detachable brush head provided with a clamp receiving stud; a handle provided with an internally threaded, longitudinal bore; a resilient clamping element adapted to connect the handle and brush head, the clamping element being formed of a material of circular section and having one end bent upon itself to form an open loop adapted pivotally to engage the stud on said brush head; a sleeve adapted to receive and substantially to enclose a portion of said clamping element extending away from said loop, and to effect a constricting action on the loop; said clamping element having a threaded portion engaging the threaded portion in the bore of said handle, and adapted thereby, upon relative rotation of the handle and sleeve, selectively to cause engagement of the free end of the sleeve with said loop, to constrict and permit expansion of said loop, about the brush stud, whereby to permit angular adjustment of, and to maintain the desired setting between, the brush head and handle.
